UNITED STATES PATENT OFFICE

JOHN E. SWANSON, OF JAMAICA PLAIN, MASSACHUSETTS

INCREASER FOR LASTS

Application filed December 9, 1927. Serial No. 238,802.

This invention relates to improvements in waist increasers or waist and instep increasers for lasts and the general object thereof is to provide a detachable device adapted when applied to a last to increase the height and breadth of the comb portion of the last thereby enabling standard lasts to be employed in the construction of shoes requiring a higher or more ample waist effect.

10 The present invention is also adapted to be employed in the manufacture of pumps and is used to increase the circumference of the upper portion of the vamp thereby preventing the edge of the vamp from biting into the foot while permitting the shoe otherwise to be so formed as properly to fit the foot.

15 A further object of the invention is to provide a waist and instep increaser for lasts which will enable a shoe having an instep strap to be so constructed that the button for the strap may be adapted for the higher waist effect and if set over for the lower waist effect will conceal the scar produced by the removal of the button.

20 25 By the use of the present invention, therefore, standard lasts employed in the manufacture of regular lines of shoes may also be adapted for use in the manufacture of special shoes such as those having higher instep effects, thereby saving the expense which otherwise would be required for special lasts.

The present invention also adds to the convenience of the shoe manufacturer in that it enables the same last to be employed for different purposes without the necessity of changing lasts when it is necessary or desirable to produce shoes having higher waist or instep effects.

30 40 These and other objects and features of the invention will more fully appear from the following description and the accompanying drawings and will be particularly pointed out in the claims.

45 50 The present invention is an improvement upon the invention disclosed in my prior Patent No. 1,180,204, granted April 18, 1916, which discloses a metallic increaser for lasts comprising a V-shaped body portion and a lateral instep portion adapted to embrace the waist and instep portions of the comb of the

last. In that construction the V-shaped body of the increaser engages the toe portion of the last with laterally extending wings which conform to the lower waist portion. The upper end of the V-shaped body is spaced apart from the last while the edges of the body portion engage the sides of the comb of the last. In the rough handling of lasts having such metallic increasers applied thereto the increasers are likely to become bruised and bent and rendered unserviceable. The present invention comprises a waist increaser for lasts comprising a pad of resilient fibrous material permanently curved to fit upon the comb of the last and provided with means for detachably securing the same to the last. The present device may be so constructed as to fit upon the combs of different lasts and of various sizes so that it is practically universally adaptable for use upon any last.

55 60 65 A preferred embodiment of the invention is illustrated in the accompanying drawings, in which,

70 Fig. 1 is an elevation of a last having an increaser embodying the present invention applied thereto;

75 Fig. 2 is a longitudinal vertical sectional view of a last with the waist increaser applied thereto;

80 Fig. 3 is a detail transverse sectional view through the increaser and stud by which it is attached to the last; and,

85 Fig. 4 is a detail sectional view illustrating the manner in which the increaser may be removed from the last by a suitable detaching tool.

90 The last illustrated in Fig. 1 is designed for the manufacture of women's shoes and comprises a toe portion 1 the ball dimension of which is illustrated by the dotted line *a*, a waist portion 2 the waist line of which is illustrated by the dotted line *b*, the instep portion 3 the instep line of which is illustrated by the dotted line *c*, and the heel portion 4. The waist increaser 5 is shown in Fig. 95 1 as applied to and fitting the upper waist and instep portion of the comb 6 of the last and extends downwardly, preferably at a point slightly below the vamp line *d* which is illustrated in dotted lines.

The increaser comprises a transversely curved pad 7 of preferably resilient fibrous material, such as leather, the lateral and lower edges 8 of which are so tapered that the curvature of the outer surface of the pad merges into the curvature of the last so that when the increaser is applied to the last it corresponds to a last having a somewhat higher waist and instep. Desirably the waist increaser is of heavy leather the grain side of the leather being upon the upper surface and the under surface of the pad so skived that when applied to the last the grain surface of the leather constitutes in effect a continuation of the curved surfaces of the waist and instep portions of the last.

As one of the objects of the invention is to provide a device which may be applied to standard lasts and removed when desired, suitable means are provided for detachably securing the increaser to the last. In the preferred construction herein disclosed a stud 9 is permanently secured to the pad and is adapted detachably to engage the walls of a suitable socket in the lower portion of the comb of the last. The lower end of the stud 9 desirably is provided with a transverse slot 10 extending well into the stud, enabling the lower ends 11 and 12 thereof to be slightly separated so that when the stud is inserted in the complementary socket in the last the sections 11 and 12 of the end of the stud will be sprung together and their resilience will cause such frictional engagement with the walls of the socket as to hold the stud firmly, but detachably, in place.

The upper end portion 13 of the stud, which extends through the pad, is of a reduced diameter, thus providing a shoulder 14 to engage the under face of the pad. Desirably a washer 15 is seated upon the shoulder 14 of the stud and engages the under face of the pad 7 into which it is desirably countersunk flush with the under face of the pad. A washer 16 also surrounds the end of the stud and engages and desirably is countersunk into the upper surface of the pad 7 so as to be flush therewith. Desirably the upper end of the stud is provided with an axial recess 17 and the wall 18 of said recess is riveted down upon the washer 16. By beveling the wall of the central hole of the washer the expanded upper end 10 of the stud will sufficiently overlie the beveled wall of the washer so that there will be substantially no interruption of the curved upper surface of the increaser.

The last, as illustrated in Figs. 2 and 3, is provided with a cylindrical socket 19 to receive the stud 9. This socket 19 desirably is of a size to provide a fairly close fit for the stud 9 so that the expanded lower end portions 11 and 12 will engage the walls of the socket with sufficient friction to retain

the increaser in place and in firm engagement with the last.

Desirably an aperture 20 extends through the increaser in proximity to the periphery of the washers 15 and 16, thus enabling a suitable tool 21 having a laterally bent point to be inserted through the hole 20 and beneath the washer 19, whereupon the increaser can be readily removed by a slight prying and pulling movement of the tool.

The aperture 20 desirably is made of the same diameter as the aperture which receives the reduced portion 13 of the stud, and is located in longitudinal axial alignment therewith thus being adapted to also receive the reduced portion of the stud. By reason of this construction, the stud may be placed in either one of the two apertures so that the pad may be placed at different distances longitudinal of the comb of the last thus enabling the waist portion of the last upper to be further increased when the stud is in the upper aperture. In either case the extracting tool may be inserted in the open aperture, and introduced beneath the washer 19 upon the stud which is fixed in the other aperture.

The increaser may be of any desired length. As illustrated in Fig. 2 it is relatively short and adapted only to increase the waist measurement of the last, while as illustrated in Fig. 1 it extends well up the instep portion of the last and serves to increase both the waist and instep. As heretofore stated, the lower end 22 of the increaser desirably extends slightly below the vamp line *d* of the usual low pump or single strap shoe, thereby slightly increasing the circumference of the upper edge of the vamp so that shoes constructed upon the last thus increased will not bite into the flesh of the foot.

The invention, however, is particularly adapted to provide a last which can be employed in the manufacture of shoes having high waists. It is a fact that the ball measurement of the foot on line *a* is slightly greater than the waist measurement of the foot on the line *b*. It, therefore, follows that in high waist effect shoes the waist measurement of the shoe must be greater than the waist measurement of the foot in order that the foot may be inserted into the shoe. A shoe upper having a high waist effect is illustrated in the dot and dash lines *e* and the increaser illustrated in Figs. 1 and 2 is designed to permit such additional fullness of the vamp as will enable the toe of the foot to be introduced into the shoe, and also to cause the shoe properly to fit around the waist portion of the foot.

The invention is also adapted for use with the "one strap" pumps or shoes in which a single strap extends over the instep. The upper of such a pump is illustrated in dotted lines *f* which also illustrates the strap *g* pass-

ing over the instep and having at its end a buttonhole *h* to receive a button which is sewed, or otherwise secured, to the quarter. In the manufacture of one strap shoes on usual lasts, the button is set according to a usual standard. If it is necessary to fit the shoe to a foot having a higher instep, the button must be set back toward the edge of the quarter, thereby exposing the scar produced by the removal of the button. By the present invention the strap is passed over the increaser and the button attached to the quarter in a position which will be proper for a high instep shoe. If the shoe is then fitted to a foot having a low instep the button will be secured further down upon the quarter so that the strap will conceal the scar left by the removal of the button.

It will thus be obvious that the present invention is adapted to many uses. It enables the regular last to be used in the manufacture of shoes having high instep effects. It provides for the manufacture of pumps in which the upper is carried above the waist line to produce the effect of a tongue as illustrated by the dotted lines *e*. It provides for the manufacture of shoes having high insteps as well as high waist effects and various other purposes well known to those skilled in the art.

The present invention enables a shoe manufacturer to make these special shoes upon regular lasts without the necessity of purchasing or carrying an additional line or lines of lasts for this purpose. The increaser, being of flexible resilient material, is adapted to fit any last and can be transferred when desired from one size last to another. It is also adapted to fit any type of last.

The apertures in the lasts to receive the stud may be readily bored at the proper place in the comb of the last either by the use of a jig, by measurements, or by the eye. It is, therefore, easily and readily applied to any type of last.

It will be understood that the embodiment of the invention disclosed herein is of an illustrative character and that various changes in material, form, and construction may be made within the spirit and scope of the following claims.

Having thus described the invention, what is claimed as new, and desired to be secured by Letters Patent, is:

1. An increaser for lasts comprising a pad of resilient fibrous material permanently curved to conform to the waist portion of the comb of the last with its lateral and lower edges tapered to merge into the curvature of the last, a stud having a split and slightly expanded lower end adapted frictionally and detachably to engage a socket in the last and having a reduced upper end portion extending through said pad and presenting a shoulder beneath said pad, a washer on said re-

duced portion engaging said shoulder and the under face of the pad, a washer on said stud engaging the upper face of the pad and curved to conform to the surface of the pad and countersunk therein with the end of the stud expanded upon said upper washer, said pad having an aperture therethrough adjacent to said washers to permit the introduction of the end of a detaching tool below the lower washer whereby the pad may be removed without distorting or otherwise damaging the same.

2. An increaser for lasts comprising a pad of resilient material shaped to conform to the waist portion of the comb of the last with its lateral and lower edges tapered to merge into the curvature of the last, a stud extending centrally through said pad having means upon its upper end to engage the surface of the pad, a washer on said stud engaging the under surface of the pad, and a shoulder upon the stud engaging said washer, said stud having an expansible lower end adapted to engage the socket in the last, said pad being provided with an aperture extending therethrough in proximity to said washer to permit the introduction of a detaching tool below said washer, whereby the pad may be removed without destroying or otherwise damaging the same.

In testimony whereof, I have signed my name to this specification.

JOHN E. SWANSON.
